UNITED STATES PATENT OFFICE.

GERHARD MATHIS, OF BROOKLYN, NEW YORK.

GUARD-CAP FOR SHADE-ROLLERS.

SPECIFICATION forming part of Letters Patent No. 729,881, dated June 2, 1903.

Application filed August 7, 1902. Serial No. 118,770. (No model.)

To all whom it may concern:

Be it known that I, GERHARD MATHIS, a citizen of the United States, residing in New York, borough of Brooklyn, and State of New York, have invented certain new and useful Improvements in Window-Shades, of which the following is a specification.

This invention relates to an attachment for the slotted bracket for supporting shade-rollers; and its object is to provide an inexpensive means whereby the accidental disengagement of the shade-roller from the brackets is prevented.

The invention consists of a guard-cap for the slotted bracket of the shade-roller comprising an annular portion frictionally engaging the barrel of the bracket and a frusto-conical portion having an open end of less diameter than the diameter of the shoulder of the pintle, upon which latter it is adapted to abut to prevent lateral displacement of the cap, and having a longitudinal slot communicating with the open end and extending through the conical portion and annular portion, as will be more fully described herein-after and finally pointed out in the claims.

In the accompanying drawings, Figure 1 is a front elevation of the spring-actuated end of a shade-roller in position in the supporting bracket. Fig. 2 is a vertical transverse section thereof on line 2 2, Fig. 1. Fig. 3 is a vertical longitudinal section on line 3 3, Fig. 2. Figs. 4 and 5 are vertical transverse sections on line 4 4, Fig. 3, showing the guard respectively in open and in closed position. Fig. 6 is a perspective view of the guard-cap; and Fig. 7 is a perspective view of the shade-roller bracket, the same being of usual construction.

Similar letters of reference indicate corresponding parts.

Referring to the drawings, A represents the shade-roller, which is provided with the usual spring-actuated pintle *a*, that is adapted to be seated in the bracket B, which latter is of usual construction, having the slotted barrel *b*. On the barrel is arranged the guard-cap C, which is annular in shape and is provided with the frusto-conical portion *c'*, which is provided with a central opening *c*², and the end of said frusto-conical portion is of smaller

diameter than the diameter of the shoulder of the pintle *a*, as shown in Fig. 3, upon which it is adapted to abut should the cap accidentally loosen, and thereby prevents the cap from becoming removed from the barrel of the bracket. The cap C is stamped from sheet metal and is provided with a longitudinal slot *c*³, and adjacent to the slot is formed the finger-stop *c*⁴. The pintle *a* is received in the opening *c*² of the cap.

In adjusting the shade the guard-cap on the bracket is turned to the position as shown in Fig. 2, so that the slot *c*³ thereof is in alignment with the slot of the barrel of the bracket. After this is accomplished the guard-cap is turned in position as shown in Figs. 1 and 5, so as to close the recess or slot of the barrel of the bracket. The cap is movable on the barrel of the bracket with sufficient friction to prevent any accidental movement of the same. In order to remove the shade-roller from the brackets, the guard-cap is turned to the position shown in Fig. 4, so as to place the slot of the guard-cap in alignment with the slot of the barrel of the bracket, thereby permitting the ready removal of the pintle therefrom.

The attachment is simple and inexpensive in construction and is adapted for use with the shade-rollers and brackets of present construction.

Having thus described my invention, I claim as new and desire to secure by Letters Patent—

1. The combination, with the shouldered pintle of a shade-roller, of a bracket having a slotted barrel, and a guard-cap movably fitted on said barrel, said cap being provided with an annular portion frictionally engaging said barrel and with a frusto-conical portion, having an open end of less diameter than the shoulder of the pintle adapted to abut upon said shoulder to prevent lateral displacement, and a longitudinal slot communicating with said opening and extending through the conical portion, and annular portion, substantially as set forth.

2. A guard-cap for shade-rollers, consisting of an annular portion and a frusto-conical portion provided with an open end adapted

to engage the pintle and to abut upon the shoulder of the pintle of the shade-roller, so as to prevent accidental displacement, said annular and frusto-conical portions being slotted longitudinally, substantially as set forth.

In testimony that I claim the foregoing as

my invention I have signed my name in presence of two witnesses.

GERHARD MATHIS.
